UNITED STATES PATENT OFFICE.

ALAN T. LOCKARD, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,158,517.

Specification of Letters Patent.

Patented Nov. 2, 1915.

Application filed September 10, 1915. Serial No. 49,855.

To all whom it may concern:

Be it known that I, ALAN T. LOCKARD, a citizen of the United States, and a resident of Suffern, in the county of Rockland and State of New York, have made and invented certain new and useful Improvements in Brake-Shoes, of which the following is a specification.

This invention relates to brake shoes and reinforcing backs therefor, an object of the invention being to so form the back that, although it is provided with an outwardly looped integral lug, the body of the shoe lying therebeneath will be reinforced and a secure anchorage will be provided therefor.

A further object is to provide a reinforcing back for brake shoes, which may be stamped from sheet metal, and which includes an outwardly looped integral lug, the sides of which are reinforced by the provision of end walls, and by brace plates which are carried thereby, the latter extending beneath and being securely anchored to the adjacent portions of the back, so as to hold the lug against opening up and the back against spreading, as well as providing a reinforcement and anchorage for that portion of the body which is located directly between the sides of the lug.

Other objects and advantages will appear as the description proceeds, wherein it is to be understood that changes in the precise embodiment of the invention can be made within the scope of what is claimed without departing from the spirit thereof.

The preferred embodiment of my invention is disclosed in the accompanying drawings, wherein:—

Figure 1 is a view in longitudinal vertical section of a brake shoe embodying the characteristic features of my invention. Fig. 2 is a view in section thereof taken on the line 2—2 of Fig. 1. Fig. 3 is a view in plan of the blank from which the back is formed. Fig. 4 is a fragmental view in perspective of the reinforcing back with its integral lug. Fig. 5 is a view partially in side elevation and partially in section of the lug portion of the back, the brace plates of the lug being secured to the back by the use of suitable rivets. Fig. 6 illustrates a somewhat further modification of the back, the brace plates in this instance being secured to the back by spot welding or analogous means. Fig. 7 is a fragmental view partially in side elevation and partially in section of the lug portion, of a form of back, wherein the brace plates are located in the general plane of the back.

Referring to the several views, the blank, illustrated in Fig. 3, is cut or stamped from sheet metal and comprises the oblong body 10, through which extend the elongated openings 11 which, in the completed or finished back, allow the molten metal of the body to flow therein, so as to increase the securing and anchorage thereof. The body 10 is slightly longer than the completed back, so that the central lug forming portion 12 may be outwardly buckled to form a looped integral lug.

The lug forming portion 12 of the blank is provided with the confronting U-shaped slits 13, which define tongues 14, the same being so located that they may be bent inwardly against the top of the lug so as to increase the thickness thereof and define key receiving openings. Projecting transversely from the lug portions 12 of the blank are the end wall portions 15, which increase in width toward their outer extremities, and carry the brace plate portions 16. The body 10 of the blank is provided at points slightly removed from the lug portion 12 with the openings 17, and the brace plate portions 16 are provided with similar openings 18, which, after the body of the blank has been buckled for the formation of the lug, and the brace plates have been bent therebelow, align with the aforementioned openings and provide for the securing of the brace plate to adjacent portions of the back. The brace plate portions are also provided with openings 19 to allow the molten metal of the body of the shoe to flow thereabove.

The blank, as thus constituted, is buckled at the lug portion 12 so as to form the integral looped lug 20, the same comprising the top wall 21 and side walls 22. The tongues 14 are turned inward beneath and into contact with the top wall 21 of the lug, and, due to the double thickness of metal thus obtained, renders unnecessary the provision of additional cast metal above the lug, as is usually resorted to in order that the distance from the top of the lug to the key openings will be of the required and

standard dimensions. The inward turning of the tongues 14 define openings 23 in the sides of the lug for the reception of the shoe attaching key.

5 The end wall portions 15 of the blank are bent downward between the sides of the lug 20, and form end walls 24 therefor. The brace plate portions 16 are bent beneath the sides of the lug and into contact with adjacent portions of the back, causing the openings 17 and 18 to register and allowing the body metal to flow up therein, so as to permanently tie and lock the two together. The brace plates 25 accordingly extend across 10 the lower open portion of the looped lug 20 and serve as a reinforcement and anchorage for that portion of the shoe body which is located directly beneath the lug and between the sides thereof. Furthermore, these brace 15 plates hold the lug from opening up and the back against spreading should the body metal of the shoe become broken or fractured. The openings 19 within the brace plates allow the body metal to flow up and 20 around the same for the secure anchorage and reinforcement of this portion of the body, as above outlined.

The reinforcing back, illustrated in Fig. 5, is similar to the foregoing with the exception that the brace plates 25 are securely held to the back by means of rivets 27 before the back is inserted within a mold and the body metal cast thereto. The brace plates may be secured to the back in any desired 30 manner, and a somewhat different form of securing is illustrated in Fig. 6, wherein the brace plates 25 are secured to the adjacent portions of the back by spot welding or analogous means, such changes and variations coming clearly within the scope of my invention. In this connection it is also to be understood that the body 26 of the shoe may include any of the usual forms of inserts or hard areas should it be so desired.

45 The protrusion of the brace plates beneath the general plane of the back may, in some instances, be objectionable, and to obviate the same, I provide the modified form of back, as illustrated in Fig. 7, wherein the 50 end walls 24' of the lug are provided with brace plates 25' of limited length, and of such size that they extend between the sides 22' of the lug and in the general plane of the back 10'. This location of the brace 55 plates allows the body of the shoe to be worn completely away, and provides for the continuous reinforcement of that portion of the body which is located beneath the lug during such wear.

60 What I claim is:—

1. A blank comprising a body with a lug forming portion, lug end wall portions carried by said body and projecting to opposite sides thereof, and brace plates carried 65 by said lug end wall portions.

2. A blank of the class described comprising a body with a lug forming portion, said body provided with openings therein spaced a slight distance from said lug forming portion, lug end wall portions projecting to opposite sides of and carried by said body, brace plates carried by said end wall portions and provided with openings therein adapted to register with the openings in said body. 70

3. A blank of the class described comprising an oblong body relatively longer than the finished back and provided with a centrally disposed lug forming portion, said lug forming portion provided with confronting U-shaped slits. 75

4. A blank of the class described comprising a body with a lug forming portion, outwardly widening lug end wall portions projecting to opposite sides of said body, and brace plates carried by said end wall portions, said lug portions provided with confronting U-shaped slits. 80

5. A blank of the class described comprising an oblong body, lug end wall portions projecting to opposite sides thereof, brace plates carried by said end wall portions, said body and said brace plates provided with openings adapted to align after the bending of said blank, said lug portion provided 90 with symmetrically arranged U-shaped confronting slits. 95

6. A brake shoe back with a looped lug, end walls carried by said lug and brace plates carried by said end walls and projecting 100 beneath the open portion of said lug.

7. A reinforcing back for brake shoes formed with a looped lug, end walls carried by and projecting downwardly from the open of said lug and brace plates carried 105 by said end walls, and projecting beneath the open extremity of said lug.

8. A back for brake shoes comprising a body formed with a looped lug, downwardly widening end walls carried by said lug and 110 brace plates carried by said end walls, and projecting across the open portion of said lug.

9. A brake shoe back formed with a looped lug, downwardly widening end walls 115 carried by the top of said lug and brace plates projecting across the open extremity of said lug and provided with openings therein.

10. A brake shoe comprising a reinforcing back formed with a looped lug, end walls carried by said lug, brace plates carried by said end walls, and projecting across the open portion of said lug, and a brake shoe body cast to said back with the metal there- 120 of extending above and anchored to the said brace plates. 125

11. A brake shoe back with a looped lug, end walls carried by said lug and brace plates carried by said end walls and pro- 130

jecting beneath and across the open extremity of said lug and anchored to said back.

12. A brake shoe comprising a reinforcing back with a looped lug, end walls carried by said lug, brace plates carried by said end walls and projecting across the open extremity of said lug, and a brake shoe body cast to said back, reinforced by said brace plates and anchoring and tying the same to said reinforcing back.

13. A brake shoe back formed with a looped lug, the sides of said lug provided

with U-shaped slits therein, defining tongues with the free extremities thereof remote 15 from the top of said lug, said tongues being bent inward and into contact with the lower surface of the top of said lug.

Signed at Chicago in the county of Cook and State of Illinois this 31 day of August 20 A. D. 1915.
